UNITED STATES PATENT OFFICE.

THEODORE DETROYES, OF VILLENEUVE-SUR-YONNE, FRANCE.

METHOD FOR SECURING LEATHER DISKS TO THE ENDS OF BILLIARD CUES.

Application filed December 15, 1925, Serial No. 75,645, and in France December 20, 1924.

My invention relates to a method for securing leather disks to billiard cues.

In my said arrangement, the disk, which consists of thick and flexible leather, is secured to a celluloid or like disk which is suitably attached to a metal ring so as to form therewith a cap into which is inserted the end of the cue.

The appended drawings show by way of example an embodiment of the invention.

Fig. 1 is a vertical section of the finished billiard disk.

Fig. 2 is a plan view of the metal ring.

My said device essentially comprises a metal ring 1 whereof one edge is provided with a flange 2, preferably striated. A celluloid disk 3 whose diameter is practically the same as the bore of the ring 1 is engaged in the latter, and is in contact with the flange 2. Another disk 4, whose diameter is the same as that of the outer diameter of the ring 1, is applied against the flange 2. I interpose between the disks 3 and 4 a layer of a special cement, based upon acetone or like solvent for celluloid, or other substance, which is shown at 5, and I exercise a suitable strong pressure, and by this means I cement the two disks together. By the use of the same cement, the billiard disk 6 which is the same as usual as regards shape and material is secured to the disk 4.

As concerns the methods of attaching the billiard disks, I thus eliminate the usual claws or teeth which are employed in certain of the known devices in order to secure the disk directly to the ring, for such claws become damaged, and are also subject to wear, and the leather disk has no longer the requisite elasticity.

By my said method I am enabled to manufacture the ring 1 in a very simple manner, and due to its construction I eliminate the complicated and fragile outfit necessary for the manufacture as well as the onerous upkeep, which characterize the known methods of mounting the billiard disks by means of claws.

By the use of celluloid or like substance which is sufficiently strong and elastic I am enabled to provide a seating for the billiard disk which is substantial as well as elastic. The disks 3 and 4 are cemented together in an approved manner so as to form a single disk co-operating with the flange 2.

The special cement has the same elasticity as the celluloid and it is also moisture-proof, so that the billiard disk will not become loose.

To obviate all play after use, I prefer to place one or more thicknesses of paper between the end of the cue and the disk 3.

Obviously, the said invention is not limited to the constructional form hereinbefore described by way of example, and the shape and disposition of the various parts of the device may be modified without departing from the principle of the invention.

For instance the disks 3 and 4 may be replaced by a single disk of the same total thickness which is in direct contact with the ring 1, or which may have a peripheral groove into which the edge of the ring is inserted, or the same is secured to the ring by any suitable means.

Having thus described my apparatus, what I claim as new therein, and my own invention, is:

1. In an arrangement for securing the billiard disks to the ends of billiard cues, the combination of a ring having a circular flange, said flange being internally disposed in such manner as to form a cap adapted for the insertion of the accurately formed end of the cue, a disk engaged in the said ring and in contact with the flange, a second disk in contact with the outer face of the said flange, the two disks being suitably secured together, and a billiard disk which is cemented to the outer face of the last-mentioned disk.

2. In an arrangement for securing the billiard disks to the ends of billiard cues, the combination of a metal ring having an internal flange which has a roughened surface, a celluloid disk engaged in the said ring and in contact with the said flange, a second celluloid disk in contact with the outer face of the said flange, the said disks being secured together, the said roughened parts of the flange entering into the said disks, and a leather billiard disk secured to the last-mentioned disk.

In testimony whereof I have hereunto affixed my signature.

THEODORE DETROYES.
